UNITED STATES PATENT OFFICE.

GEORGE W. COX, JR., OF WASHINGTON, DISTRICT OF COLUMBIA, ASSIGNOR TO NATIONAL ASSORTING COMPANY, OF WASHINGTON, DISTRICT OF COLUMBIA, A CORPORATION OF DELAWARE.

SORTING MACHINE.

Application filed May 6, 1922. Serial No. 559,020.

To all whom it may concern:

Be it known that I, GEORGE W. Cox, Jr., a citizen of the United States, residing at Washington, in the District of Columbia, have invented certain new and useful Improvements in Sorting Machines, of which the following is a specification.

This invention relates to sorting machines, and it has for its object among others to provide a simplified form of sorting machine in which conveyor belts and other forms of conveying means are dispensed with, the device being key-operated, and having its component parts so constructed and arranged that a multiplicity of promiscuously arranged papers may be sorted into their proper order by one manipulation of each instead of necessitating a series of operation in order to bring about the final result as has been the practice heretofore. This invention not only effects a great saving of time but dispenses with complicated mechanisms as well as economizing in space. Furthermore, the device is easily manipulated, not liable to get out of order, and is absolutely reliable and certain in its results. Not only do I accomplish the desired result in much less time, but I do so with practically one-third the labor required where heretofore at least three manipulations have been necessary to sort the papers into their final arrangement.

Furthermore, papers may be sorted into classes of arrangement either by number, letter, or other designation, such for instance as where checks are thrown into groups according to the names of banks; where papers are thrown together by names or locations; etc. In fact it may be said that there is practically no limit of uses of the machine in the assortment of checks, tickets, coupons, or other papers, provision being made for readily handling the papers, irrespective of their thickness or dimensions.

Other objects and advantages of the invention will hereinafter appear and the novel features thereof will be particularly pointed out in the appended claims.

The invention is capable of embodiment in a variety of forms, that herein shown being given for the purpose of illustration only and is not to be in any wise construed

as the necessary or only embodiment of the invention.

The invention in its preferred form is clearly illustrated in the accompanying drawings which, with the numerals of reference marked thereon, form a part of this specification, and in which—

Figure 1 is a top plan of my improved sorting machine.

Figure 2 is a front elevation thereof.

Figure 3 is a front elevation of one of the movable leaves with portions beneath the same in section, as on the line 3—3 of Figure 1.

Figure 4 is a side elevation of the device with portions broken away, with the cover removed.

Figure 5 is an elevation looking at the opposite side of the machine with a portion only of the cover shown, the remainder of the cover being removed.

Figure 6 is an enlarged detail in side elevation showing by dotted lines the position assumed by one of the movable leaves when moved for the insertion of a paper.

Figure 7 is an enlarged perspective detail, with portions broken away, showing one of the movable leaves and its attached finger, with a paper shown in dotted lines held thereby.

Figure 8 is a detail in plan view, with the triggers shown in section.

Figure 9 is a vertical cross section on the line 9—9 of Figure 4, looking in the direction of the arrows.

Figure 10 is a perspective view of the cover, removed.

Figure 11 is a view similar to Figure 3, showing a modified form of construction.

Like numerals of reference indicate like parts throughout the several views.

Referring to the drawings:

Numerals 1 designates a base of suitable material and size, which may rest upon a table or other support, or may be provided with legs or the like 2 of any suitable character, to support the machine in any position or under any circumstances or conditions of use. Rising from each corner of the base are uprights 3, suitably secured to the base in any suitable manner, as by screws or the like 4, see Figure 2. The

shape, size, and height of these uprights 3 may vary under the conditions of use.

At the upper ends of these corner uprights there are secured the side strips 5, 5 while on the front end is secured to the front uprights the transverse strip 6, and at the rear end to the rear uprights is secured the transverse strip 7. The front and rear transverse members 6 and 7 are provided upon their upper edges with vertically disposed slots 8, so that the said members 6 and 7 each constitute what might be termed a comb, each of the slots being designed to receive and to provide for ready 10 sliding movement of the bars, soon to be described, and designed for actuation of the movable leaves. Any suitable means, such as a strip 9, seen in Figure 2, may be provided to prevent upward displacement of 15 20 the bars from their slots while being manipulated. As seen in Figure 1, I preferably, though not necessarily, provide the transverse member 10, which is likewise slotted, as seen at 11, the slots, however, extending 25 from the lower edge of the strip upward and serving to guide the bars in their movement and prevent upward as well as lateral displacement during manipulation.

The bars 12 which may be of any 30 desired number, but in the present form of embodiment of the invention I employ fifty. Each bar is mounted for sliding movement in aligning slots in the members 6, 7 and 10, as will be readily understood upon reference 35 to Figure 1, and in the present embodiment of the invention each of these bars has fixedly secured thereto so as to move therewith depending lugs or the like 13, in the present instance ten on each bar, and which 40 serve as triggers for manipulating the leaves soon to be described.

Each of these bars 12 carries a finger piece 14, each bearing a designation, said 45 designations being either all odd, all even, or all in sequence, as may be desired, the numbers in the present instance being odd numbers running from 1 to 99, and being also staggered, as seen in Figure 1, that is, the first bar at the left is numbered 1, the 50 next bar 3, the next 5, the next 7, the next 9, and then the next set runs from 11 to 19, so that, as will be readily seen from Figure 1, all of the designations ending in "1" will be 55 arranged in one row, as considered transversely of the machine, all those ending in 3 extending transversely in one row, and so on. In lieu of these numerals any other designations may be placed upon the finger pieces of the bars.

60 In the form of construction now being described each depending lug or trigger 13 moves a series of leaves as the bar 12 is moved, as will be made clear as the description proceeds. Each bar is restrained against movement by means of a spring 15,

one for each bar, said springs being attached at their forward end to the rear end of a bar 12 and at their rear end to a transverse member 16 secured to the side pieces 5 by forwardly extending portions 17, as 70 seen in Figure 1. A transverse bar 18 serves to limit the rearward movement of the bars when released from the pressure exerted on the finger pieces and retracted by the springs. In order that the springs may not interfere with each other in the movement of the bars I sometimes arrange such springs in different vertical planes, as indicated in Figure 1, each alternate spring being disposed above and below the cross member 18, the upper springs being attached to the upper edges of the bars and the lower springs to the lower edges of such bars. 75

As before stated the construction herein shown and described is intended to be symbolic only of the generic character of the invention and in no wise descriptive of the only form of structural embodiment thereof, and with this understanding the foregoing as well as the following explanation is made. 80

Therefore, referring to Figure 4, there will be seen transverse members or cleats 19, of which there are in the present instance ten, each cleat being firmly secured to the base by any suitable means, integral therewith if desired. These members 19 serve not only as spacers for the groups of leaves but also as a support therefor when in their rearward positions and as stops for the same in their forward movement. As seen in Figures 4 and 5 the spaces 20 between two adjacent transverse strips 19 are greater than the combined thickness of 10 the leaves 21 which are arranged in groups, one group in each of said spaces. This is to provide room for freedom of movement of the leaves and also to compensate for the thickness of the papers inserted between the 11 leaves of each group in the operation of the machine. The number of leaves in each group can vary ad libitum, dependent upon the character of the sorting for which each particular machine may be devised. These 12 leaves 21 are formed of any suitable material, preferably aluminum, for sake of lightness of weight as well as ease of manipulation, and in the present instance I have chosen to describe each group as comprising fifty leaves; and each of these leaves 21 carries a spring finger 22, seen clearly in Figure 7, one finger being secured to each leaf at the inner end of the finger, leaving the finger free for the ready insertion of a paper, check, or the like, 24, shown in dotted line in said Figure 7, inserted between the finger 22 and the leaf 21. 13

Each leaf of each group is mounted for freedom of movement, and while this may 14

be accomplished in a variety of ways I have in the present instance shown each leaf as provided at the bottom edge with a portion 25 inclined forwardly from the body of the leaf, and this inclined portion is provided at each end with a notch 26 extending inwardly, as will be understood upon reference to Figure 7, and in assembling the parts each of these slots or notches loosely 10 receives the horizontal member 27 of an angle-iron 28, provided upon each side of the machine with the vertical portions thereof of being secured to the base 1 in any suitable manner as by screws or the like 29, see 15 Figure 3. Thus each group of leaves has each leaf freely movable, as upon a pivot, and by reason of the inclination of the portion 25 when a leaf or leaves of a group is or are moved by manipulation of the proper 20 bar, the remainder of the leaves in each group toward the rear do not have a tendency to follow up those moved; that is, those not positively moved by the manipulation of the bar retain their position, inclined toward the rear of the machine, thus 25 leaving a V-shaped opening between the selected leaves for the ready insertion of the paper intended therefor.

Each leaf 21 is provided with an upwardly extending lug or projection 30, as seen in Figure 3, and each of these projections is of materially greater dimensions in the direction of the length of the leaf than the thickness of the trigger 13 which is designed 25 to engage the same, as will be readily seen by reference to Figure 8, and these projections or lugs 30 are staggered across the width of the machine and overlap, as seen in Figure 8, so that one "backs up" the other, thus giving 40 strength to the material and tending to avoid bending the same when the trigger 13 is pressed against the lugs 30, especially when the trigger is required to move a multiplicity of the leaves.

45 It may sometimes be found necessary to assist the rearward or return movements of the groups of leaves, and when this becomes necessary I provide for each group a spring finger or strip 31, each of said spring fingers 50 being secured to a transverse member 19, as seen in Figures 4 and 5, except that the front spring 31 is secured to the base 1, as seen in Figure 2 at 31^a. This spring should be of such character as not to offer material 55 resistance to the forward movement of the groups of leaves during the operation of the machine but sufficient to assist gravity in aid in returning the groups of leaves to their normal or rearward position.

60 As means of protection to the leaves, which, as seen in Figures 1 and 2, project beyond the left-hand side plate of the machine for a purpose which will be readily understood after the operation of the device 65 is proceeded with, I provide at front and

rear a protector plate 32 secured to the uprights 3, as shown at 33, see Figure 2.

Each leaf 21 may be of any desired form, that shown in Figure 3 having been found very efficient, the material at top and bottom being removed for sake of lightness, and the outer or left-hand end of each is preferably cut away upon an incline or otherwise as seen at 34 in Figures 2 and 3, so as to permit of vertical adjustment of the supporting platform or shelf now to be described, so as to accommodate the device to sort papers of greater or less width, or vertical dimensions.

This support or platform 35 may be or may not be used, but when employed is secured to the left-hand side of the machine, as, for instance, to one of the uprights 3, which latter is provided with a vertically elongated slot 36, in which is engaged a thumbscrew or the like 37 mounted in the front member of the platform or support 35 to accommodate it to different heights of papers. As seen in Figure 1 this platform or support is preferably provided with a plurality of vertically arranged dividers 38 or the like 38, so as to form a plurality of compartments 39, one opposite each group of leaves. It will be understood of course that a provision similar to that provided at the front of the device for vertical adjustment of the platform or support, is also made at the rear of the machine.

In order to house and protect the parts I employ a cover 40, seen removed in Figure 10, having at the front of the top an opening 41, through which project the finger pieces 14, and cut away at the left-hand side, as shown at 42, to provide space for the movement of the projecting portions of the leaves 21, and along this edge of the cover at the top I provide the index strip 43, secured thereto as shown in Figure 10, the said index strip being inclined outwardly and downwardly, as seen in Figures 2 and 10, the designations on this strip corresponding to the groups of leaves, as will be readily understood.

It may sometimes be desirable to sort papers into two or more longitudinal rows, and for this purpose I provide the form of leaves shown at 44, in Figure 11, with a plurality of extensions 45 beveled upon their under sides, as seen at 46, and each carrying a spring finger 47, the numeral 48 indicating an upwardly extending lug for engagement by the trigger 13 on the actuating bar as heretofore explained. These leaves are mounted for movement in the same manner as those above described, and their mode of operation is identically the same, except that the leaf is provided for sorting of multiplicity of rows disposed transversely of the machine.

In machines designed for certain purposes

the spring fingers 22 on the leaves may be dispensed with, while in machines designed for other purposes it may be desirable to use more than one spring finger on each leaf.

5 With the parts constructed and arranged substantially as hereinbefore described, the operation briefly stated is as follows:

The mail matter, envelopes, checks, cards, or whatever it may be desired to sort, ar- 10 ranged promiscuously, are placed on a table or any other suitable means of support ar- ranged within convenient reach of the operator who stands or sits at the front end of the machine, and are picked up one by 15 one, or otherwise, for ready insertion into the appropriate space or pocket formed be- tween the leaves at the left-hand side of the machine. In the above described form of construction and assuming that there are 20 fifty leaves in each group the operator would begin the sort with a pile of papers with numbers thereon running, say, from 1 to 1,000, all in promiscuous condition. He 25 would pick up any one of the papers and readily perceiving the number to be, say for instance, 120, would carry the paper opposite the index number "1" on the index strip 43 at the left-hand side of the machine, at practically the same time he pulls 30 forward finger piece numbered 21. This forward movement of the finger piece causes the bar 12 to which it is attached to move forward and in doing so the lug 13 on said bar engages the upstanding lug 30 on the 35 front leaf in each group moving forward the front leaf of each group, the leaves of each group to the rear of the actuated leaves not being affected but remaining in place. This movement provides an opening or 40 pocket in each group between the leaf moved and the one next adjoining it at the rear. Each leaf with its spring finger serves for holding two checks or papers, the last or right-hand figure or digit of which is either 45 an even or an odd number. If the first paper handled has an odd number the paper is placed between the spring finger 22 and the leaf to which it is attached; but if it be an even number, as in the case supposed, 50 the check or paper is placed between the said spring finger and the leaf next adjacent in front. This having been done the check or paper will be found in the pocket or space representing the number 120. Supposing, 55 for instance, that the number of the paper selected had been 121, the same mode of procedure would be followed except that the paper would be placed in the space between the spring finger and the leaf to which it 60 is attached, and thus the paper would be in the space representing the number 121. This mode of procedure is followed with all of the papers. Another example, say with the check numbered 763, the paper is car- 65 ried opposite the group designated "7" on the index member 43, the finger piece numbered 63 is pulled forward thus moving forward its bar 12 and the appropriate leaf, in this case the thirty-second leaf from the front in each group so as to separate such leaf from the one next adjacent at the rear, and the paper or check, its last or right-hand digit being 3 (an odd number) is placed in the opening between the spring finger and the leaf by which it is carried; 70 had the number been 762, the paper or check would have been placed in front of the spring finger, that is, between such spring finger and the leaf next adjacent toward the front. This mode of procedure is followed with each and every paper to be sorted. As soon as the paper is in proper position pressure is removed from the finger piece, and the spring 15 returns the bar to its normal position, the leaves also all grav- 75 itate to their normal or rearward position, and the next appropriate bar is moved for the insertion of the next paper. It is to be understood that, in this form of construction, the properly positioned papers are held only at their right-hand end, as indicated in dotted lines in Figure 7, leaving a greater or less portion of the paper projecting beyond the outer ends of the leaves where they 80 can be readily grasped in any desired quantity by the hand of the operator for removal, after all or any desired number of the papers have been sorted. These projecting ends or portions of the papers are supported upon the platform 35, the partitions or members 85 38 serving to retain the papers of each group in appropriate position. As the papers are removed from the machine they should of course be taken in numerical order in what- 90 ever quantity desired and placed in such position that when all have been removed the numbers will read consecutively from top to bottom. 95

It will be noted that by the use of this device one handling of the papers is all that is necessary up to the time that they are finally removed from the machine, when all will be found in correct numerical order.

When any one finger piece is moved the bar moved therewith causes actuation of 100 all of the correspondingly numbered leaves, for instance, if the finger piece numbered 21 is moved its bar will actuate the leaf to open the pocket 21 in each and every one of the groups of leaves. By this means the one key serves for manipulation of the appropriate leaf to open the desired pocket or space in all of the groups, the advantages of which will be readily seen. Of course the operator will soon learn to disregard all 105 open pockets except the one in the group into which the paper or check in hand is to be inserted, as indicated by the number on the strip 43. For instance, if the paper to be inserted is numbered 241 the first impulse 110

120

125

130

is to move the hand to the "two hundred" group on the strip 43 and all that is necessary is simply to drop the paper in the space provided therefor by the manipulation of 5 the appropriate finger piece.

The modification shown in Fig. 11, as before stated, is provided for the purpose of sorting two or more longitudinal rows of papers, it being obvious that as many rows 10 as desired may be assorted, by providing the necessary number of extensions 45. The construction shown in Fig. 11 may be utilized to sort two rows of 1,000 papers each, the odd numbers being placed beneath the 15 spring fingers 47, and the even numbers between said finger and the leaf next in front.

This modification is also adapted for the sort of 1,000 papers, in two parallel rows of 20 500 each, the spring fingers 47 being dispensed with in such operation. It is to be understood that, in such a sort, there will be two longitudinal rows of groups 21, and two rows of compartments 39, also that each 25 of the finger pieces 14 will be provided with two sets of numbers, one preferably above the other, and the bottom number being 50 points higher than the top number. In other words, referring to the five staggered 30 finger pieces 14, in the approximately vertical rows of finger pieces on the left, in Figure 1, the top finger piece 14 would bear the numbers 1 and 51; the next to the top piece would carry the numbers 2 and 52, etc., throughout all of the rows of keys, so 35 that the last finger piece of the row, at the extreme right, would bear the numbers 50 and 100.

In operation, every check or paper carrying numbers such that the last two digits aggregate fifty or less, would be placed in the row at the left of the machine, and those in which the last two digits run from fifty-one to one hundred, inclusive, are placed in 45 the row at the right. Specifically, in locating the position for the number 763, the operator pulls forward the finger piece bearing the numeral 63, and this movement will cause the forward movement of the 50 thirteenth leaf from the front in each group in both longitudinal rows of the groups 21. Since the numeral 63 is in excess of fifty, and the first number on the paper is 7, the operator places the check in the opening 55 formed in the right hand row and opposite the numeral 7 carried by the strip 43.

If the next paper selected is No. 121, the operator pulls the finger piece bearing the numeral 21, and places the paper in the opening provided in the left hand row opposite the number 1 carried by the strip 43.

When the 1,000 papers are all sorted, as just described, it will be obvious that the group 21 at the front of the left hand row 60 will contain in proper order all papers num-

bered 1 to 50, inclusive; that the group immediately opposite in the right hand row will contain papers numbered 51 to 100, inclusive; that the next to the front group on the left will contain papers numbered 101 70 to 150, and the opposite row to the right will contain papers numbered 151 to 200, etc., etc. In abstracting the papers after the sort is completed, the operator first pulls out all of the papers in the front group of the row 75 to the left; then removes the papers in the front group of the row to the right, placing them behind the papers first abstracted; then the next to the front group in the row to the left, etc., until all of the papers are 80 taken from the machine, and they will be found to be in exact order.

From the foregoing description, it should be readily understood that, in each embodiment of my invention herein described, I 85 have provided spaces for 1,000 checks, or other papers, by the utilization of 500 leaves, arranged in ten groups of 50 leaves each, in combination with 50 triggers, each of which is adapted for actuation to simultaneously cause a V-shaped opening to be provided between corresponding and similarly located leaves of all of the ten groups. I have also provided an index strip 43, whereby the operator is apprised as to the 90 proper opening in which to deposit the paper, dependent upon the indicia carried by the latter. It will be understood, therefore, that the checks, as herein described, are assorted by the terminal and sub-terminal indicia carried thereby.

For instance, in the examples given in the foregoing description of the operation of the device, in the process of positioning the check numbered 763, the numerals 63 constitute the terminal index, and the numeral 7 the sub-terminal index. In locating the space for a paper of this number, the operator first glances at the third number from the last, in this instance the number 7, and moves the paper up to the group of leaves immediately below the numeral 7 on the strip 43. A trained operator will almost simultaneously note that the last two numbers are 63, and will have pulled the finger 105 piece bearing the number 63, so that, by the time the paper has reached a point adjacent the group of leaves under the number 7 on the strip 43, the appropriate space will have been provided between the leaves in each 110 group (in this case leaves 32 and 33 in each group) and the operator then places the paper under or in front of the spring clip 22, dependent upon the terminal designation, in this instance, since the terminal 115 designation is an odd number, the check being placed under the clip 22.

The same general principle of operation will prevail in the alphabetical sort, the finger pieces bearing letters of the alphabet, 120 125 130

and the strip 43 also bearing the letters of the alphabet. In the sort of an article bearing the name "Parker", for instance, the a finger piece is pulled, opening a space under 5 each of the letters on the strip 43, and the article is dropped into the space under the letter P; on the second sort the letters r and k are simultaneously considered; next the letters e and r.

10 This identical principle is carried out with invoice slips, sales slips, etc., bearing a plurality of arbitrary letters, symbols or numbers, or any combination of letters, symbols and numbers. In all cases, such designations are placed on the finger pieces as 15 will identify them with certain designations carried by the articles being sorted, and such indicia are placed upon the strip 43 as will correspond with other indicia carried by the 20 articles being sorted.

The machine herein described and shown is practically "fool proof" inasmuch as while there is practically no likelihood of the paper being improperly placed in the 25 sorting of the papers, each space or pocket is designed to contain but one paper and therefore if at any time the operator should find a paper, say, for instance, number 870 for insertion, and he finds the 870 space 30 occupied, he at once knows that the paper in such space was incorrectly deposited or that it is a duplicate, and he can readily remove the same and put it in its proper place, or, if it be a duplicate, this fact is 35 readily detected. Under some conditions, however, a machine may have pockets or spaces each of which may contain a multiplicity of papers. For instance, in a machine designed for sorting bank checks 40 where it may be desired to place all the checks on one bank together regardless of their numerical order, the space or pocket would be correspondingly enlarged and the finger pieces correspondingly designated, 45 and in this instance only one leaf for each of such pockets would be required. Again, the finger pieces may be designated by letters or other indicia in accordance with the character of the work to be done by the 50 machine. These and various other modifications in detail, as well as proportion of parts, etc., I should deem as clearly coming within the scope of my invention, and I therefore do not wish to be restricted to 55 the exact details, designations, proportion of parts, etc., as hereinbefore disclosed, but reserve the right to make such changes, variations, and modifications as come properly within the scope of the appended 60 claims.

What is claimed as new is:

1. The method of sorting promiscuously arranged articles which consists in simultaneously providing a multiplicity of spaces 65 classified for the reception of articles of like

designations, and inserting an article in a space classified in accordance with another designation carried by the article.

2. The method of sorting a multiplicity of promiscuously arranged papers into a plurality of appropriate groups which consists in simultaneously providing paper-receiving spaces in each group and then inserting the appropriate paper in proper place in its appropriate group. 75

3. The method of sorting a multiplicity of promiscuously arranged papers into a plurality of appropriate groups which consists in simultaneously providing paper-receiving spaces in each group and then inserting the appropriate paper in proper place in its appropriate group, leaving portions of such papers exposed to facilitate removal. 80

4. The method of sorting a multiplicity of promiscuously arranged papers into a plurality of appropriate groups which consists in simultaneously providing paper-receiving spaces in each group and then inserting the appropriate paper in proper place in its appropriate group, the papers being placed on edge with a portion of each exposed to facilitate removal. 85

5. In a sorting machine, a multiplicity of movably mounted leaves arranged into a plurality of groups and means for simultaneously moving a correspondingly positioned leaf in all the groups. 95

6. In a sorting machine, a multiplicity of movably mounted leaves arranged into a plurality of groups and means for simultaneously moving a correspondingly positioned leaf in all the groups, and paper-retaining means carried by the leaves. 100

7. In a sorting machine, a plurality of groups of leaves mounted for independent movement and means for simultaneously moving a selected leaf of each group, said leaves being mounted to maintain normal position by gravity. 105

8. In a sorting machine, a multiplicity of groups of leaves, each group comprising a multiplicity of movably mounted leaves, and means for simultaneously laterally moving corresponding leaves in each group. 110

9. In a sorting machine, a multiplicity of groups of leaves, each group comprising a multiplicity of movably mounted leaves, and means for simultaneously separating corresponding leaves in each group, each side of each leaf serving as a support for two differently designated papers to be deposited thereinbetween. 115

10. In a sorting machine, a multiplicity of groups of leaves, each group comprising a multiplicity of movably mounted leaves, held in normal position by gravity, and means for simultaneously separating corresponding leaves in each group. 125

11. In a sorting machine, a multiplicity 130

- of independently movably mounted leaves arranged to form a group, actuators for said leaves each leaf being provided with means for engagement by an actuator, said means on each leaf being arranged in overlapping staggered relation, with respect to the means on the adjacent leaf. 65
12. In a sorting machine, a leaf having a fulcrum portion inclined with relation to the body of the leaf, leaf-actuating means, and means on said leaf adapted for engagement by its actuating means. 70
13. In a sorting machine, a leaf-supporting member, and a leaf having its lower portion extending at an angle to the body thereof and provided with a slot adapted to receive said member. 75
14. In a sorting machine, a leaf-supporting member, a leaf actuator, a leaf having its lower portion extending at an angle to the body thereof and provided with a slot adapted to receive said member, the upper edge of said leaf being provided with a lug adapted for engagement with said actuator. 80
15. In a sorting machine, a supporting frame, a leaf having its lower portion extending at an angle to the body thereof, said leaf having a portion extending beyond the frame of the machine to provide a support for papers being assorted, substantially as described. 85
16. In a sorting machine, a supporting frame, a leaf having its lower portion extending at an angle to the body thereof, said leaf having a portion extending beyond the frame of the machine, and provided with a paper-holding member, substantially as described. 90
17. In a sorting machine, a supporting frame, a leaf having its lower portion extending at an angle to the body thereof, said leaf having a portion extending beyond the frame of the machine, and provided with a resilient paper-holding member, substantially as described. 95
18. In a sorting machine, a leaf having its lower portion extending at an angle to the body thereof, and constituting a support for the leaf, a reciprocating leaf-actuator, and a lug on the upper edge of said leaf adapted for engagement by said actuator in its reciprocation. 100
19. In a sorting machine, a leaf having its lower portion extending at an angle to the body thereof, and constituting a support for the leaf, a reciprocating leaf-actuator, a lug on the upper edge of said leaf adapted for engagement by said actuator in its reciprocation, and means for returning said actuator to normal position, after each reciprocation thereof. 105
20. A sorting machine provided with a plurality of pivotally mounted elements arranged into groups containing an equal number of elements and adapted to receive papers therebetween, in combination with means for simultaneously pivotally moving like elements in the several groups, to provide paper-receiving spaces therebetween, substantially as described. 110
21. A sorting machine provided with a plurality of leaves arranged in groups, indicia denoting the classification of each group, and means for simultaneously moving a selected leaf in each group to provide paper-receiving spaces adjacent said leaves, substantially as described. 115
22. A sorting machine provided with a plurality of leaves arranged in groups, indicia denoting the classification of each group, means for simultaneously separating a selected leaf in each group from the adjacent leaf of its group to provide a paper receiving space between adjacent leaves, and means carried by the leaves for indicating the selected space into which a paper is to be inserted. 120
23. A sorting machine comprising a multiplicity of movably mounted leaves arranged into a plurality of groups containing an equal number of leaves; each leaf in each group having a different classification, but the different groups having corresponding leaf classifications, and means for simultaneously moving the leaves of the same classification in all of the groups. 125
24. A sorting machine comprising a multiplicity of movably mounted leaves arranged in a plurality of groups containing an equal number of leaves, each leaf in each group having a different classification, but the different groups having corresponding leaf classifications, and means for simultaneously moving the leaves of the same classification in all of the groups, in combination with indicia denoting a different classification for each group. 130
25. In a sorting machine, a multiplicity of groups of leaves independently movably mounted, actuators for said leaves, and indicia on each of said actuators, classifying it with certain leaves in each group. 135
26. In a sorting machine, a multiplicity of groups of leaves independently movably mounted, reciprocatory actuators for said leaves, and indicia on each actuator classifying it with certain leaves in each group. 140
27. In a sorting machine, a multiplicity of groups of leaves independently movably mounted, actuators for said leaves, indicia on each actuator classifying it with certain leaves of each group, and means whereby actuation of a selected actuator simultaneously moves a corresponding number of leaves in each group. 145
28. In a sorting machine, a multiplicity of groups of leaves independently movably mounted, reciprocatory actuators for said

- leaves, indicia on each actuator classifying it with certain leaves of each group, and means whereby actuation of a selected actuator simultaneously moves a corresponding number of leaves in each group. 5 carried by the articles being sorted, and indicia carried by the machine denoting the group appropriate for the reception of each article, as indicated by the sub-terminal designation carried by the latter. 65
29. In a sorting machine, a multiplicity of groups of leaves independently movably mounted to be held in their normal position by gravity, reciprocal actuators for said leaves, means on each actuator classifying it with a certain leaf of each group, and means whereby actuation of a selected actuator simultaneously moves a corresponding number of leaves in each group. 10 70
- 10 30. A sorting machine comprising a multiplicity of spaced elements so arranged in groups containing an equal number of elements that similarly positioned elements of each group have the same classification, and means for simultaneously moving all the elements of the same classification in each group. 15 75
- 15 31. A sorting machine comprising a multiplicity of spacing elements so arranged in groups containing an equal number of elements that similarly positioned elements in each group have the same classification, indicia denoting the classification of each group, and means for simultaneously moving all the elements of the same classification of each group. 20 80
- 20 32. A sorting machine comprising a multiplicity of spacing elements so arranged into a plurality of groups containing an equal number of elements that correspondingly positioned elements of all the groups have the same classification, and a plurality of actuators each of which is adapted for reciprocation to move only the elements of 25 85
- 25 the same classification in each group. 30 90
- 30 33. A sorting machine for articles bearing terminal designations comprising a multiplicity of spacing elements so arranged into a plurality of groups containing an equal number of elements that correspondingly positioned elements of all groups have the same classification, and means adapted for actuation to simultaneously provide, between adjacent elements, an article-receiving space 35 95
- 35 of the same classification in all the groups, and in accordance with the terminal designations carried by the articles being sorted. 40 100
- 40 34. A sorting machine for articles bearing terminal and sub-terminal designations, comprising a multiplicity of spacing elements so arranged into a plurality of groups containing an equal number of elements that correspondingly positioned elements of all the groups have the same classification, a plurality of actuators each of which is adapted for reciprocation to simultaneously provide an article-receiving space of the same classification in all the groups, and in accordance with the terminal designations 45 105
- 45 carried by the articles being sorted, and indicia carried by the machine denoting the group appropriate for the reception of each article, as indicated by the sub-terminal designation carried by the latter. 50 110
- 50 35. The method of sorting promiscuously arranged papers, in accordance with the terminal and sub-terminal designations carried thereby, which consists in simultaneously providing a plurality of spaces appropriate for the terminal designation, of a paper and inserting the paper in the space appropriate to the sub-terminal designation. 55 115
- 55 36. A sorting machine comprising a multiplicity of spacing elements arranged in a plurality of groups positioned in separate rows, each group containing an equal number of elements, and each element of each group in each row having a separate classification, in combination with means for moving in unison elements of the same classification in every group in each row, substantially as described. 60 120
- 60 37. A sorting machine comprising a multiplicity of members positioned in parallelism and each carrying spacing elements forming a plurality of rows arranged in groups containing an equal number of elements, and means for simultaneously moving members of the same classification in each group. 65 125
- 65 38. A sorting machine comprising a multiplicity of members positioned in parallelism and each carrying spacing elements forming a plurality of rows arranged in groups containing an equal number of elements, and means for simultaneously moving members of the same classification in each group, said means comprising a movable actuator adapted for movement to simultaneously engage members of the same classification in each group. 70 130
- 70 39. A sorting machine comprising a plurality of movable leaves arranged in groups, an actuator adapted for movement to separate a correspondingly positioned leaf of each group from the leaf adjacent thereto, and means for automatically returning said leaves to their normal position. 75 135
- 75 40. A sorting machine comprising a plurality of movable leaves arranged in groups, an actuator adapted for movement to separate a correspondingly positioned leaf of each group from the leaf adjacent thereto, means for automatically returning said leaves to their normal position, and means for automatically returning said actuator to its normal position. 80 140
- 80 41. A sorting machine comprising a plurality of movable leaves arranged in groups, an actuator adapted for movement to separate a correspondingly positioned leaf of each group from the leaf adjacent thereto, and means for automatically returning said 85 145

leaves to their normal position, said means comprising a resilient element bearing upon the front portion of each group of leaves and tending to restore the moved leaves of said portion to their normal positions.

42. A sorting machine comprising a plurality of pivotally mounted leaves arranged in groups and held in a normal position by gravity, an actuator adapted for movement to separate a correspondingly positioned leaf of each group from the leaf adjacent thereto, and means for assisting gravity in the restoration of said leaves to normal position.

43. A sorting machine comprising a plurality of leaves arranged into groups, and a plurality of leaf actuators, each actuator being adapted upon movement to provide a space between correspondingly positioned leaves of each group.

44. A sorting machine comprising a plurality of movably mounted leaves arranged in groups, each leaf being provided with an abutment, and an actuator common to leaves of the same classification in each group and provided with a projection adapted to contact the abutment on said leaves only, upon movement of said actuator.

45. A sorting machine comprising a frame, a plurality of movably mounted leaves arranged in groups and extending laterally across the frame, an abutment so positioned on each leaf as to form a series of staggered abutments across the frame for each group of leaves, and a series of actuators extending longitudinally of the frame, each actuator carrying projections adapted, upon movement of the actuator, to contact only the abutments of a series of correspondingly positioned leaves of the several groups.

46. A sorting machine comprising a frame, a plurality of movably mounted leaves arranged in groups and extending laterally across the frame, an abutment so positioned on each leaf as to form a series of staggered abutments across the frame for each group of leaves, a series of actuators extending longitudinally of the frame, each actuator carrying projections adapted, upon movement of the actuator, to contact only the abutments of a series of correspondingly positioned leaves of the several groups, and means for automatically restoring said leaves to normal position.

47. A sorting machine comprising a frame, a plurality of movably mounted leaves arranged in groups and extending laterally across the frame, an abutment so positioned on each leaf as to form a series of staggered abutments across the frame for each group of leaves, a series of actuators extending longitudinally of the frame, each actuator carrying projections adapted, upon

movement of the actuator, to contact only the abutments of a series of correspondingly positioned leaves of the several groups, and means for automatically restoring said leaves to normal position, said means comprising a resilient element bearing upon the front portion of each group.

48. A sorting machine comprising a frame, a plurality of movably mounted leaves arranged in groups and extending laterally across the frame, an abutment so positioned on each leaf as to form a series of staggered abutments across the frame for each group of leaves, a series of actuators extending longitudinally of the frame, each actuator carrying projections adapted, upon movement of the actuator, to contact only the abutments of a series of correspondingly positioned leaves of the several groups, means for automatically restoring said leaves to normal position, and means for automatically restoring each actuator to its normal position.

49. A sorting machine comprising a frame, a plurality of movably mounted leaves arranged in groups and extending laterally across the frame, an abutment so positioned on each leaf as to form a series of staggered abutments across the frame for each group of leaves, a series of actuators extending longitudinally of the frame, each actuator carrying projections adapted, upon movement of the actuator, to contact only the abutments of a series of correspondingly positioned leaves of the several groups, means for automatically restoring said leaves to normal position, and means for automatically restoring each actuator to its normal position, said means comprising a resilient element connected to said actuator and to the said frame.

50. A sorting machine comprising a plurality of movably mounted leaves arranged in groups, each containing an equal number of leaves, an abutment carried by a correspondingly positioned leaf in each group, an actuator common to said correspondingly positioned leaves and provided with projections positioned for contact with said abutments, upon movement of said actuator, and indicia carried by the actuator classifying it with said leaves.

51. A sorting machine comprising a frame, a plurality of movably mounted leaves arranged in groups and extending laterally across the frame, an abutment so positioned on each leaf as to form a series of staggered abutments across the frame for each group of leaves, a series of actuators extending longitudinally of the frame, each actuator carrying projections adapted, upon movement of the actuator, to contact only the abutments of a series of correspondingly positioned leaves of the several groups, and indicia carried by each actuator classifying it with said leaves.

ing it with said leaves of the same classification in each group.

52. A sorting machine comprising a plurality of movably mounted leaves arranged in groups, each group containing an equal number of leaves, an abutment carried by a correspondingly positioned leaf in each group, an actuator common to said correspondingly positioned leaves and provided with projections positioned for contact with said abutments, upon movement of said actuator, and indicia carried by the machine denoting the classification of each group.

53. A sorting machine comprising a frame, a plurality of movably mounted leaves arranged in groups and extending laterally across the frame, an abutment so positioned on each leaf as to form a series of a staggered abutments across the frame for each group of leaves, a series of actuators extending longitudinally of the frame, each actuator carrying projections adapted, upon movement of the actuator, to contact only the abutments of a series of correspondingly positioned leaves of the several groups, indicia carried by each actuator classifying it with said leaves of the same classification in each group, and indicia carried by the machine denoting the classification of each group.

54. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, and actuators extending longitudinally of the frame and provided with projections, each of which is adapted, under movement of its actuator, to contact the abutment of and move one of the corresponding leaves of the same classification in each group.

55. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one of the corresponding leaves of the same classification in each group, and indicia carried by each actuator classifying it with leaves of the same classification in each group.

56. A sorting machine comprising a frame, a multiplicity of movably mounted

leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one of the corresponding leaves of the same classification in each group, and means automatically assisting gravity in the restoration of said shifted leaves to normal position.

57. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one of the corresponding leaves of the same classification in each group, and means automatically assisting gravity in the restoration of said shifted leaves to normal position.

58. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one of the corresponding leaves of the same classification in each group, and means for automatically restoring said actuators to normal position.

59. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one

of the corresponding leaves of the same classification in each group, and means for automatically restoring said actuators to normal position, said means comprising a resilient element connected to each actuator and to said frame.

60. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one of the corresponding leaves of the same classification in each group, indicia carried by each actuator classifying it with leaves of the same classification in each group, and means for automatically assisting gravity in the restoration of said leaves to normal position.

61. A sorting machine comprising a frame, a multiplicity of movably mounted leaves adapted to maintain a normal position by gravity, and arranged in a plurality of groups which extend laterally of the machine and project outwardly therefrom, indicia carried by the frame and denoting the value of each projecting group of leaves, an abutment carried by each leaf, actuators extending longitudinally of the frame and provided with projections, each of which is adapted, under movement of its actuator, to contact with the abutment of and move one of the corresponding leaves of the same classification in each group, indicia carried by each actuator classifying it with leaves of the same classification in each group, and means for automatically assisting gravity in the restoration of said leaves to normal position, said means comprising a resilient member mounted to oppose movement of said leaves from normal position.

62. A sorting machine comprising a frame, a multiplicity of pivotally mounted leaves extending transversely of the frame and projecting therefrom in a plurality of separated groups, a series of actuators extending above and transversely of the leaves, abutments so positioned on each leaf as to form a row of staggered abutments extending transversely of the frame for each group of leaves, projections carried by each actuator and adapted, under movement of the latter, to contact with the abutment of and simultaneously shift similarly classified leaves in all the groups, indicia carried by each actuator classifying it with the classification of certain leaves in

all the groups, a housing for said actuators, and indicia carried by said housing, adjacent said groups, denoting the classification of the latter, substantially as described.

63. A sorting machine comprising a frame, a multiplicity of pivotally mounted leaves extending transversely of the frame and projecting therefrom in a plurality of separated groups, a series of actuators extending above and transversely of the leaves, abutments so positioned on each leaf as to form a row of staggered abutments extending transversely of the frame for each group of leaves, projections carried by each actuator and adapted, under movement of the latter, to contact the abutment of and simultaneously shift similarly classified leaves in all the groups, indicia carried by each actuator classifying it with the classification of certain leaves in all the groups, a housing for said actuators, indicia carried by said housing, adjacent said groups, denoting the classification of the latter, and means automatically tending to restore said shifted leaves to normal position, substantially as described.

64. A sorting machine comprising a frame, a multiplicity of leaves mounted for oscillatory motion and extending transversely of the frame and projecting therefrom in a plurality of separated groups, a series of actuators extending above and transversely of the leaves, abutments so positioned on each leaf as to form a row of staggered abutments extending transversely of the frame for each group of leaves, projections carried by each actuator and adapted, under movement of the latter, to contact the abutment of and simultaneously shift similarly classified leaves in all the groups, indicia carried by each actuator classifying it with the classification of certain leaves in all the groups, a housing for said actuators, indicia carried by said housing, adjacent said groups, denoting the classification of the latter, and means automatically tending to restore said actuators to normal position, substantially as described.

65. A sorting machine comprising a frame, a multiplicity of pivotally mounted leaves extending transversely of the frame and projecting therefrom in a plurality of separated groups, a series of actuators extending above and transversely of the leaves abutments so positioned on each leaf as to form a row of staggered abutments extending transversely of the frame for each group of leaves, projections carried by each actuator and adapted, under movement of the latter, to contact with the abutment of and simultaneously shift similarly classified leaves in all the groups, indicia carried by each actuator classifying it with the classification of certain leaves in all the groups, a housing for said actuators, indicia carried

by said housing, adjacent said groups, denoting the classification of the latter, means automatically tending to restore said shifted leaves to normal position, and means 5 automatically tending to restore said actuators to normal position, substantially as described.

66. A sorting machine comprising a multiplicity of spacing elements in separated rows each element of each row having 10 a different classification, by position, with a fixed variance of classification assigned to similarly positioned elements of the separated rows, and means for simultaneously 15 moving similarly positioned elements of each row.

67. A sorting machine comprising a multiplicity of spacing elements so positioned in groups which are arranged in separated rows that there is a fixed variance 20 of classification between elements of all of the groups of one row with respect to correspondingly positioned elements of the groups of another row, and means for simultaneously moving similarly positioned elements of each group of each row.

68. The method of sorting promiscuously arranged articles bearing a plurality of designations, which consists in simultaneously 30 providing a plurality of spaces of the same classification and in accordance with one designation carried by an article, and in thereafter depositing said article in a space 35 subclassified in accordance with another designation carried by said article.

69. The method of sorting promiscuously arranged articles bearing terminal and sub-terminal designations, which consists in simultaneously providing a plurality of 40 spaces of the same classification in accordance with the terminal designation of an article, and in thereafter depositing the

article in one of said spaces classified in accordance with the sub-terminal designation thereof.

45

70. A device for sorting promiscuously arranged articles bearing a plurality of designations, including means for simultaneously providing a plurality of spaces of the same classification and in accordance 50 with one of the designations carried by an article, in combination with means classifying such spaces in accordance with another designation carried by said article.

71. The method of sorting promiscuously arranged articles bearing classifying indicia which consists in simultaneously providing a plurality of spaces of like classification in accordance with certain of the indicia carried by the article, depositing an article 60 in a space classified in accordance with certain other indicia carried thereby, and thereafter clamping said paper in said space.

55

72. A machine for sorting promiscuously arranged papers having distinguishing indicia thereon, comprising means for simultaneously providing a plurality of spaces of like classification with respect to a portion 65 of the indicia on the various papers, and means for automatically clamping a paper 70 in position after its deposit in one of said spaces.

65

73. The method of sorting promiscuously arranged articles which consists in simultaneously providing a multiplicity of spaces 75 classified for the reception of articles of like designations, in accordance with an index carried by the article being sorted, and inserting the article in a space classified in accordance with another index carried by 80 the article.

In testimony whereof I affix my signature.

GEORGE W. COX, JR.
